Patented Oct. 17, 1922.

INVENTOR
ADOLPH F. FELLER

BY Chas. E. Townsend

ATTORNEY

UNITED STATES PATENT OFFICE.

ADOLPH F. FELLER, OF OAKLAND, CALIFORNIA, ASSIGNOR, BY MESNE ASSIGNMENTS,
TO ROBT. W. MICHAEL, OF SAN FRANCISCO, CALIFORNIA.

FUEL CHECK AND LOCK FOR CARBURETOERS.

Application filed April 7, 1920. Serial No. 371,906.

To all whom it may concern:

Be it known that I, ADOLPH F. FELLER, a citizen of the United States, residing at Oakland, in the county of Alameda and State of California, have invented a new and useful Improvement in Fuel Checks and Locks for Carburetors, of which the following is a specification.

This invention relates to a fuel check and lock for carburetors and especially to a manual control operable from the dashboard of an automobile, whereby the float actuated valve of the carburetor may be closed and locked.

One of the objects of the present invention is to provide a simple substantial easily installed device for automobiles, whereby theft or operation of an automobile by unauthorized persons may be prevented, and especially to provide a device whereby the fuel supply to the carburetor may be shut off and locked.

Another object of the invention is to provide a device whereby the float actuated valve of a carburetor may be opened and closed, and especially to provide a device operable from the dashboard of a car for opening and closing the float actuated valve, and further to provide means operable in conjunction therewith for locking the valve when in closed position.

Other objects will hereinafter appear.

The invention consists of the parts and the construction, combination and arrangement of parts as hereinafter more fully described and claimed, having reference to the accompanying drawings, in which—

Fig. 1 is a central vertical section through a carburetor showing the application of the invention.

Fig. 2 is a detail view of the key actuated part of the locking mechanism.

Referring to the drawings in detail, A indicates a standard form of carburetor, 2 a spray nozzle, 3 the mixing chamber, 4 the float chamber, 5 the float, 6 the lever to which the float is attached; and 7 the valve actuated thereby. The valve 7, together with the float cooperating therewith, serves the function of automatically maintaining a

predetermined fuel level within the float chamber with relation to the spray nozzle 2, and fuel is delivered thereto from any suitable source by a copper tube 8, which is connected with the carburetor, as at 9.

Formed on the valve is a stem 10, to which the float lever is attached, and adapted to engage the upper end of the stem is a spring actuated plunger 11, which in this instance is mounted in a fitting 12. The lower end of this fitting is threaded and is screwed into the connection as at 13, it being here secured by any suitable means such as a pin or by soldering. The upper end of the fitting 12 is connected through a tube 14 with a sleeve 15, which in turn is supported by and secured in a lock housing 16. Slidably mounted in the sleeve 15 is a draw rod 17, on the outer end of which is formed a head member 18; and forming a connection between the draw rod and the plunger 11 is a flexible wire 19. Interposed between the upper end of the fitting 12 and the plunger proper is a spring 20, which normally serves the function of depressing the plunger 11 and the valve 7, thereby retaining it in engagement with the valve seat 21; and formed on the draw rod is an annular locking groove 22 and a plurality of annular grooves 23, the function of which will hereinafter be described.

Mounted within the lock casing 16 is a latch 24, and forming a portion of said latch is a latch plate 25, which is connected with a pair of springs 26. These springs normally serve the function of retaining the latch 24 in engagement with the grooves formed in the draw rod, but means are provided for withdrawing the latch against the spring tension. This is accomplished by providing a key opening 27, through which a key may be inserted. A second opening is formed in the latch plate, as at 28, and shoulders 29 formed in the lower part of said opening are adapted to be engaged by the key when inserted and turned, said engagement of the key with the shoulders 29 causing depression of the latch plate and latch, and thereby permitting free movement of the draw rod 17.

The present mechanism is provided for the purpose of preventing theft of an automobile, or operation of the same by unauthorized persons; this being accomplished by 5 closing the fuel supplying valve 7 and locking the same when in closed position.

Another function of the device is that of closing the fuel supplying valve without locking the same. For instance it often 10 happens that a carburetor leaks and it is therefore desirable at times to close the fuel supplying valve while the car is standing still, or when placed in a garage overnight.

The lock housing 16, together with the 15 sleeve and draw rod supported thereby, is preferably secured on the dashboard or instrument board of an automobile within convenient reach of the driver, it being secured in any suitable manner, or as here 20 shown by screws 30. If the driver of a car wishes to leave the same and wishes to prevent theft of the car or operation by unauthorized persons, he merely grasps the knob 18 and pushes the draw rod inwardly 25 until the annular locking groove 22 is engaged by the latch 24. He may then remove the key and can safely leave the car as fuel cannot enter the carburetor through the supply line 8, due to the fact that the 30 valve 21 is positively locked on its seat as it is held in this position by the spring actuated plunger 11. Upon returning and again desiring to use the car, he merely inserts the key and depresses the latch plate, 35 together with the latch 24. This releases the draw rod and it is therefore only necessary to pull it in an outward direction. Outward movement of the draw rod exerts a pull on the wire 19 and similarly on the 40 plunger 11, thereby raising this against the tension of the spring 20 a sufficient distance to permit free movement of the valve 7, the lever 6 and the float 5. Fuel is in this manner automatically supplied and the carburetor may therefore function in its normal or usual manner. If after using the car, and stopping for any length of time, he may again close the valve 7 by pushing the rod 17 inwardly, but not sufficiently far 45 to bring the annular groove 22 into alignment with the latch. In other words the draw rod is only forced inwardly a sufficient distance to close the valve 7, or to hold it against its seat, and it is temporarily 50 locked in this position due to the fact that the latch is in engagement with one or another of the annular grooves 23. The car may therefore stand for an indefinite period and no leakage can take place as the fuel supply 55 is shut off; this being particularly desirable when the car is placed in a garage overnight. The driver may lock the fuel supply valve, if he desires by pushing the rod 17 inwardly until the latch engages the annular groove 60 22, but this is not always necessary. Hence

the provision of one or more annular grooves such as shown at 23.

From the foregoing it can be seen that a fuel check and lock has been provided which positively prevents theft or operation 70 of a car; further that means are provided for locking the fuel supplying valve; if desired, or for merely closing the same if desired; and further that the entire mechanism employed is operable from the dashboard or instrument board, thereby eliminating any inconvenience to the driver 75 when using the mechanism.

While a more or less specific form of key actuated lock is here shown, it is obvious 80 that any other suitable form of lock may be employed, similarly while the device is here described as employed in conjunction with a carburetor, it is obvious that it is useful for other applications and uses. I similarly 85 wish it understood that the materials and finish of the several parts employed may be such as the experience and judgment of the manufacturer may dictate or varying 90 conditions may demand.

Having thus described my invention, what I claim and desire to secure by Letters Patent is—

1. The combination with the float chamber in a carburetor and a float mounted 95 therein, of a fuel supplying valve adapted to be automatically opened and closed by the float, a stem on the valve, a spring actuated plunger engageable with the stem and adapted to normally retain the valve in 100 closed position, a flexible wire connected with the spring actuated plunger, a tube enclosing the wire, a sleeve with which said tube is connected, a draw rod slidably mounted within the sleeve, a connection between 105 said wire and the draw rod, and means for locking the draw rod against movement.

2. The combination with the float chamber in a carburetor and a float mounted therein, of a fuel supplying valve adapted to be automatically opened and closed by the float, 110 a stem on the valve, a spring actuated plunger engageable with the stem and adapted to normally retain the valve in closed position, a flexible wire connected with the spring actuated plunger, a tube enclosing the wire, a sleeve with which said tube is connected, a draw rod slidably mounted within the sleeve, a connection between said 115 wire and the draw rod, a plurality of annular grooves formed on the rod, a spring actuated latch engageable with said grooves to lock the rod in predetermined positions, and a key actuated means for withdrawing the latch with relation to the draw rod.

3. The combination with a carburetor on an automobile having a float chamber formed therein, of a float in the chamber, a fuel supplying valve adapted to be automatically opened and closed by the 120

float, a draw rod mounted on the dashboard of the automobile, means for locking said draw rod, a plunger on the carburetor adapted to close the fuel supplying valve, 5 and a flexible connection between said plunger and the draw rod.

In testimony whereof I have hereunto

set my hand in the presence of two subscribing witnesses.

ADOLPH F. FELLER.
